Primary Examiner — Kevin K Rudzinski*Assistant Examiner* — Paul D Bohannon(74) Attorney, Agent, or Firm — Dinsmore & Shohl LLP(57) CLAIM

The ornamental design for a furniture riser, as shown and described.

DESCRIPTION

FIG. 1 is a top perspective view of the furniture riser;
 FIG. 2 is a top view of the furniture riser of FIG. 1;
 FIG. 3 is a side view of the furniture riser of FIG. 1; and,
 FIG. 4 is a bottom view of the furniture riser of FIG. 1.
 The broken lines show components of the furniture riser that form no part of the claimed design.

1 Claim, 2 Drawing SheetsFIG. 1*FIG. 2
